UNITED STATES PATENT OFFICE.

GUIDO ANTONI AND UGO ANTONI, OF PISA, ITALY.

FLEXIBLE-RIB FRAME FOR AEROPLANE-WINGS.

1,323,385.

Specification of Letters Patent.

Patented Dec. 2, 1919.

Application filed May 6, 1916. Serial No. 95,917.

To all whom it may concern:

Be it known that we, GUIDO ANTONI, draftsman, and Ugo ANTONI, employee, subjects of the King of Italy, residents of Pisa, in the Kingdom of Italy, No. 1 Via Cappuccini, have invented new and useful Improvements in Flexible-Rib Frames for Aeroplane-Wings, of which the following is a specification.

0 The object of the present invention is a frame with flexible ribs for aeroplane wings enabling the alteration of the curvature of the supporting surfaces through contraction of the frame without setting up strains dangerous to the stability of the flying machine or to the deformability of its parts, and without substantially altering the nature or form of the curvature although its pitch is varied.

10 The annexed drawings show, by way of example, one embodiment of the invention.

Figure 1 is a longitudinal section of the wing frame and shows in dotted lines the contracted curvature (with the convexity turned upward) that the flexible rib can assume.

Fig. 2 shows a rib for the so called "wing's equilibrium zone" where as indicated in dotted lines, the curvature assumed through contraction has a convexity turned downward.

Fig. 3 shows a rib element or spar in plan.

Fig. 4 shows the same rib element in elevation.

15 Fig. 5 shows to a larger scale two portions of the rib, viz., the front portion and the portion connected to the second cross girder.

Fig. 6 is a plan showing the portion of the rigid frame comprised between the two rigid cross girders, relatively to which girders the flexible longitudinal ribs can be deformed.

Fig. 7 shows a cross girder portion fitted with a plate for distributing the stresses set up by the bracing wires.

Fig. 8 is a section through 8—8 in Fig. 7.

Fig. 9 is a section through 9—9 in Fig. 5.

The constructional and form details may of course be varied from those shown and herein described, the arrangement yet remaining within the compass of the present invention.

The rib is constructed as shown Fig. 1 or Fig. 2, according to its position in the wing. The ribs S (Fig. 1) are used in the zone where a downward movement of the

free or rear ends of the ribs is required while the ribs S' (Fig. 2) are used in the zone where an upward movement of the free ends of the ribs is required. In both cases the 60 ribs consist of an upper spar —a— and a lower spar —b— (respectively —a'— and —b'—) held invariably apart at their front ends by a spacing piece —o— which may be provided with lightening holes, and one or 65 both of the spars —a— and —b— are capable of sliding in stirrup shaped brackets —d— secured to the center cross girder —l_c— (Fig. 5). In the rib S (Fig. 1) the thickness of the spars —a— and —b—, 70 starting from the supporting point A on the center cross girder, tapers both toward the front end C and the rear end B. In the rib S' (Fig. 2) the spar thickness remains constant from A' to the front end C' and tapers 75 from A' to the rear end B'. Figs. 3 and 4 show in plan and elevation respectively a spar with uniform breadth and tapering thickness. The front portion of the rib is stiffened by means of iron straps —h— wound 80 around it and riveted either to the spar or to distance pieces forced between the strap windings and the side wall —c—. The rib S or S' is hinged to the front cross girder —l_a—; to this end (see Fig. 5) a window e 85 is formed in the front portion of the rib and, as may be seen from the figure, the bottom portion of the left hand window-side is curved forward while the top portion of the right hand window-side is curved backward 90 so as to increase the window width accordingly and to allow the rib to pivot on the cross girder l_a (the opposite sides of which are made slightly convex) from the position shown in full lines to that shown in dotted lines on operation of the corresponding control by the pilot. The top and bottom window-sides also are curved, the convex face 95 of the curve being turned inwardly. Angle pieces —f— screwed to the cross girder alone 100 are provided to prevent the rib from moving laterally with respect to the window —e—.

Due to the construction just described the rib S (Fig. 1), on operation of the corresponding control by the pilot, can be contracted in the portion comprised between the front cross girder —l_a— and the central cross girder —l_c— (Fig. 5), the rib still passing through the middle points of the cross sections of the said cross girders; in 110 order to facilitate this, the spars are made capable of sliding in the brackets —d—.

Figs. 1 and 2 show in dotted lines the profile which can be assumed by the ribs S and S' respectively. By this arrangement, while the pitch or sag of the rib curve is varied, 5 the nature and shape of the curve are not considerably altered.

As the front and central cross girders are not rigidly connected by the ribs, in order to enable the ribs to shift their position 10 when the curve is altered, provision must be made to make the system of the two cross girders rigid. This is achieved by means of stays *i* rigidly secured to the cross girders by angle plates *r*, these angle plates in 15 their turn being secured in place with screws; one of these screws is an eye-screw and serves for attachment of the bracing wires.

In correspondence to the connections of 20 the stays *i* with the cross girders *l* and *l_c* specially shaped plates *p* are provided, the object of which is to distribute over a larger cross girder area any stresses set up by the wing suspension wires. 25 The plates *p* are straddled over the cross girder and have a tail piece *q* at the top and two extensions *s* at the bottom for attachment of the tensioning wires.

Having now described our invention and 30 how the same is to be carried out, what we claim as our invention, is:

1. In an aeroplane wing, the combination with a rigid central cross-girder, a rigid front cross-girder and a rear cross-girder, of 35 ribs comprising spars having a uniform width and a thickness tapering from the middle to both ends thereof, a pivotal connection between the rib and the said front girder and a sliding connection between the 40 rib and the said central girder.

2. In an aeroplane wing, the combination with a rigid front cross-girder, a rigid central cross-girder and a rear cross-girder, of 45 a rib comprising spars having a uniform width and a thickness tapering from the middle to one end thereof, a pivotal connection between the rib and the said front girder and a sliding connection between the rib and the said central girder.

50 3. In an aeroplane wing, the combination with a rigid front cross-girder, a rigid cen-

tral cross-girder and a rear cross-girder, of ribs comprising an upper and a lower spar having a uniform width and a thickness tapering from the middle to both ends thereof, 55 a stiffening web connecting the upper and lower spars with one another at their front ends, said web having an opening fitting said front girder, the curved sides of said opening being arranged with their convexity directed 60 inwardly, angle pieces on said front girder to prevent any lateral displacement of said rib, and brackets on said central girder slidably engaged by said spars.

4. In an aeroplane wing, the combination 65 with a rigid front cross-girder, a rigid central cross-girder and a rear cross-girder, of ribs comprising spars having a uniform width and a thickness tapering from the middle to both ends thereof, a pivotal connection 70 between said rib and front girder, a sliding connection between said rib and central girder, stays extending between and at right angles to said front and central girders and rigidly secured thereto, and diagonal bracing wires stretched between said front and central girders.

5. In an aeroplane wing, the combination with a rigid front cross-girder, a rigid central cross-girder and a rear cross-girder, of 80 ribs comprising spars having a uniform width and a thickness tapering from the middle to both ends thereof, a pivotal connection between said rib and front girder, a sliding connection between said rib and central girder, stays extending between and at right angles to said front and central girders and rigidly secured thereto, diagonal bracing 85 wires stretched between said front and central girders, and stress distributing plates 90 straddling the portions of said front and central girders adjacent said stays and provided with means for attachment of the wing tensioning wires and bracing wires.

In testimony whereof we hereunto affix 95 our signatures in the presence of two witnesses.

GUIDO ANTONI.
UGO ANTONI.
